CLAIM

The ornamental design for a vehicle locator, as shown and described.

DESCRIPTION

FIG. 1 is a front elevational view of a vehicle locator showing my new design, with the broken line showing for illustrative purposes only and forming no part of the claimed design;

FIG. 2 is a right side view thereof;

FIG. 3 is a reduced perspective view thereof;

FIG. 4 is a left side view thereof;

FIG. 5 is a bottom view thereof;

FIG. 6 is a top view thereof; and,

FIG. 7 is a rear view thereof.

The broken-line showing of environmental structure in FIG. 3 is for illustrative purposes only and forms no part of the claimed design.
